[57] CLAIM

The ornamental design for notched pool cue, as shown and described.

DESCRIPTION

FIG. 1 is a perspective view of a notched pool cue showing my new design;

FIG. 2 is a front elevation thereof;

FIG. 3 is a front elevation of a second embodiment of FIG. 1;

FIG. 4 is a front elevation of a third embodiment of FIG. 1;

FIG. 5 is a bottom plan view of FIGS. 2, 3 and 4; and FIG. 6 is a top plan view of FIGS. 2, 3 and 4.
